UNITED STATES PATENT OFFICE.

CHARLES BOTTEREL PERKINS, OF SAN FRANCISCO, CALIFORNIA.

DESIGN FOR A FLAG.

SPECIFICATION forming part of Design No. 27,006, dated May 4, 1897.

Application filed March 15, 1897. Serial No. 627,707. Term of patent 31 years.

To all whom it may concern:

Be it known that I, CHARLES BOTTEREL PERKINS, a citizen of the United States, residing at the city and county of San Francisco, 5 in the State of California, have invented and produced a new and original Design for Flags, of which the following is a full, clear, and exact specification.

The leading feature of my design consists 10 of a field divided diagonally into two contrasting portions, the lower portion displaying a fanciful figure and the upper portion displaying a small flag.

The drawing shows an elevation or side 15 view of a flag embodying my design.

The entire surface of the flag is divided by a diagonal line A into two fields B C, which are given contrasting colors. In the lower right-hand field B is displayed a fanciful

figure D, the outline of which is a split or 20 open ring. In the upper left-hand field C appears a small uncolored flag E, having the representation of a bear and a single star. The small flag E appears as flying from a pole F, rising from the field B and having the 25 cords and tassels G depending from its upper end.

Having thus described my invention, what I claim, and desire to secure by Letters Patent, is—

The design for a flag as herein described and shown.

In testimony whereof I hereunto set my signature in the presence of two witnesses.

CHARLES BOTTEREL PERKINS.
